UNITED STATES PATENT OFFICE.

SHERMAN A. RANK, OF CHICAGO, ILLINOIS.

DISPLAY APPARATUS.

Application filed April 12, 1920. Serial No. 373,128.

To all whom it may concern:

Be it known that I, SHERMAN A. RANK, a citizen of the United States, residing at the city of Chicago, in the county of Cook and State of Illinois, have invented certain new and useful Improvements in Display Apparatus, of which the following is a specification.

This invention relates to new and useful improvements in display apparatus of the type involving a mechanically operated dancing figure.

One of the principal objects of my invention is to provide a dancing figure which is yieldably supported in co-operative relation with a vibratory platform.

Another object of the invention is to provide a simple and effective means for yieldably supporting the platform.

A still further object of the invention is to provide a novel cam structure for vibrating the platform.

In the drawings, which illustrate one embodiment of my invention,

Figure 1 is a vertical longitudinal sectional view, and

Figure 2 is a horizontal sectional view taken directly above the platform and actuating means therefor.

Similar reference numerals indicate corresponding parts throughout the figures of the drawings.

Referring to the drawings, my invention includes a frame structure which comprises side members 5—5 and end members 6—6^a, spaced uprights 7 and 8 suitably connected to each side member 5, and a cross-bar 9 connecting the uprights 7—7 at a point above the frame members 5 and 6.

A platform 10 is pivoted at one end to the end member 6^a by flat springs 11—11. This platform extends substantially from the wall 6^a to the wall 6, but terminates a little short thereof. A cross-bar 12 is suitably connected to the side members 5—5. A re-bent or U-shaped flat spring 13 has one end suitably connected to the cross-bar 12 and its other end connected to the under side of the platform 10 at a point remote from the pivot end thereof.

A roller 14, having its axis arranged in a plane parallel with the axis of the pivot of the platform, is provided at its ends with bearing pins 15 and 16, which are respectively journaled in brackets 17—17 secured to the upright frame members 7—7. This

roller 14 is disposed adjacent the free end of the platform 10, or, in other words, adjacent that end opposite the pivot end of said platform. Fixedly secured to the roller 14 is a plurality of flexible cam fingers 18—18, which, in this instance, are formed of leather. The fingers 18 are of sufficient length to engage the free end of the platform 10 and cause said platform to be intermittently depressed and released during constant rotation of the roller 14. From the foregoing, it will be seen that the roller 14 and fingers 18 constitute a cam, the roller constituting the body of the cam and the leather fingers 18, the cam fingers. The end member 6 of the frame structure is formed with a recess 19 to permit the free passage of the cam fingers 18 during their rotation. Any suitable means may be provided for operating this cam, but, in this particular instance, I have shown a hand-crank 16^a, which is connected to the pivot pin 16.

Fulcrumed on the cross-bar 9 is a lever 20, and fixedly secured to one end of this lever is a display dancing figure, which is indicated as a whole by the reference letter A. Although figures of different forms may be readily substituted, I have illustrated a human figure having a body 21, and arms 22—22, the latter being pivoted to the body, as at 23. The figure also includes two multi-jointed legs, each leg including an upper portion 24, a foot 25 and a connecting portion 26. The upper portion 24 is pivoted to the body, as at 27, and the intermediate portion 26 is pivoted to the upper portion 24, as at 28, and the foot 25 is pivoted to the intermediate portion, as at 29. The weight of this figure is balanced by a spring 30, which, at one end, is connected to the cross-bar 9 of the frame structure, as at 31, and which, at its other end, is adjustably connected by means of a screw 32 to the end of the lever 20 opposite the display figure A. By means of the spring 30 and the adjusting screw 32, the display figure can have its normal vertical position relative to the platform 10 adjusted to a nicety.

The upright frame members 7 and 8 are suitably connected at their upper ends with cross-bars 33. The upright members 7 and 8 and cross-bars 33 constitute a supporting structure for an open-front canopy 34, which permits inspection of the dancing figure from the front end of the apparatus only. This canopy, as will be noted, also

encloses the cam structure for vibrating the platform.

In operation, the figure A is first vertically adjusted so that the feet 25 thereof will have more or less contact with the platform 10 when the latter is in its normal position, as shown in Figure 1. Upon operation of the cam, the platform 10 will be depressed downwardly against the tension of the spring 13, and this downward movement will tend to permit the leg members of the figure to assume positions in vertical alignment; that is, the pivots 27, 28 and 29 of each leg will, at times, be positioned in alignment and in a plane at substantially right angles to the plane of the platform 10. As a result, the platform 10, as it returns to its normal position after being disengaged by one of the flexible fingers 18, will exert an upward thrust against the figure, and, inasmuch as the pivots above mentioned are in alignment, a similar upward movement will be imparted to the figure. At other times, the pivots of the leg members will not be positioned as above described, so that the figure, as a whole, will not be elevated. Under these conditions, the intermittent movements of the platform will impart swinging movements between the various leg members of the figure, so as to cause said figure to assume all sorts of grotesque dancing positions.

Having thus described my invention, what I claim is:

1. In a display apparatus, the combination with a frame structure, of a platform pivoted at the front end to said frame structure, a spring for yieldably supporting said platform in a substantially horizontal plane, a display figure disposed above and in co-operative relation with said platform,

and means engageable with the rear end and upper side of the platform for vibrating said platform to transmit movements to said display figure. 45

2. In a display apparatus, the combination with a frame structure, of a platform pivoted at the front end to said frame structure, a U-shaped spring for yieldably supporting said platform in a substantially horizontal plane, one end of said spring being fixedly secured to said frame structure and the other end of said spring being fixedly secured to the platform at a point remote from the pivot end thereof, a display figure disposed above and in co-operative relation with said platform, and elastic means engageable with the rear end and upper side of the platform for vibrating said platform against the tension of said 50 U-shaped spring. 55

3. In a display apparatus, the combination with a frame structure, of a platform pivoted at the front end to said frame structure, a spring for yieldably supporting said platform in a substantially horizontal plane, a display figure disposed above and in co-operative relation with said platform, and means for vibrating said platform to transmit movements to said display 65 figure, said vibrating means including a roller arranged adjacent the rear end of the platform and having its axis arranged in a plane parallel with the axis of the pivot of said platform, elastic cam fingers carried 70 by said roller for engaging the upper face and adjacent end of said platform, and means for actuating said roller. 75

In witness whereof, I have hereunto set my hand at Chicago, Cook County, Illinois, 80 this 9th day of April 1920.

SHERMAN A. RANK.
